Charles H. Kuhn, Indianapolis, Ind.

Application June 26, 1945, Serial No. 601,622

4 Claims. (Cl. 46—61)

1

This invention relates to a toy usable in primarily two different manners, one in the nature of the popularly designated "yo-yo" and the other as in the case of a pair of buttons strung on a looped string wherein the loops are pulled outwardly and released inwardly as the buttons wind and unwind substantially intermediate the ends of those loops.

A primary purpose of the present invention is to provide a unique stringing of the toy to permit secure anchorage of the string to the body of the toy whereby the one string may serve in both usages as above indicated without having to change the string attachment or disengage one member from another making up the toy.

Other advantages will become apparent to those skilled in the art in the following description of one particular form of the toy with reference being made to the accompanying drawing, in which

Fig. 1 is a view in end elevation and partial section;

Fig. 2, a similar view showing a modified form of string attachment;

Fig. 3, a view similar to that shown in Fig. 1 with the toy disposed for horizontal winding and unwinding between outwardly pulled looped ends of the string; and

Fig. 4, a view in side elevation.

Like characters indicate like parts throughout the several views in the drawing.

I mount a pair of disc like members 10 and 11 on a common pin 12 to have a space 13 left therebetween. The members 10 and 11 are rounded from their outer faces toward the inner opposing faces defining the space 13, these inner faces being planar and parallel one with another.

The members 10 and 11 are respectively provided with transverse passageways 14, 15 and 16, 17 extending transversely therethrough spaced from the axis of the pin 12 to have the passageways 14 and 15 on a common axis and the passageways 16 and 17 on another common axis, the two axes being preferably 180° apart. In the form of the invention illustrated in Figs. 1 and 3, the member 10 is first assembled on the pin 12 and then the end of a string 18 is placed along a side of the pin 12, and preferably across its outer end, and then the member 11 is fixed over that end of the pin to compressibly engage the string within the member socket along side of the pin 12. The string 18 is threaded from along side of the pin 12 radially outwardly and then carried through the passageway 16 to the external face of the member 11; thence diametrically across to enter

2

and be carried through the passageway 17 on across the space 13; through the passageway 15; diametrically across the outer side of the member 10; back through the passageway 14 and thence outwardly between the members 10 and 11 through the space 13 to extend by a desired length and carry in its outer end portion a button or stop member 19 of such dimensions that it may not be entered within the space 13. This forms a very secure anchoring of the string 18.

Referring to Fig. 2, a variation of the threading of the string through the members 10 and 11 is indicated. The members 10 and 11 and the pin 12 may be identical with those members as indicated in Fig. 1. In this instance however an end of the string 18 is provided with a knot 20 in its end opposite the end to which the button 19 is secured. For securing that button 19, the free end of the string is carried from the knot 20 through the passageway 16; across the space 13 and on out through the passageway 14 of the member 10; diametrically across the outer face of that member 10 and back through the passageway 15; across the space 13; through the passageway 17 of the member 11; diametrically across the outer side of the member 11; back through the passageway 16; and thence outwardly between the two members 10 and 11 within the space 13 to have the button 19 secured to its outer end.

In either form with the string extended as shown in Figs. 1 and 2, the toy is then ready to be used in the usual manner by winding the string initially around the pin 12 within the space 13 (passing around the transversely extending portions of the string adjacent the pin 12) and then allowing the body composed of the members 10, 11 and 12 to roll downwardly in a string unwinding manner and then upwardly as the string rewinds.

However, the stringing of the string in either instance permits the toy to be used as indicated in Fig. 3 wherein the string 18 is pulled outwardly from the sides of the members 10 and 11 to form the loops 21 and 22 whereby the button 19 is pulled down to contact the two members 10 and 11 with the string 18 pulled tautly therefrom. Preferably the members 10 and 11 are provided with the respective recesses 23 and 24 across which the string normally passes when in the positions indicated in Figs. 1 and 2, to permit the ends of one's fingers to be engaged about those portions of the string to pull them outwardly into the loops 21 and 22.

With the string thus looped the body of the toy may be rolled downwardly or upwardly over

the body of the operator while he holds the loops 21 and 22 in outward positions so that those loops become twisted. Then by alternately pulling outwardly on the loops and then slightly releasing them, the body will spin on the string to wind and unwind.

While I have herein shown and described my invention in the forms now best known to me, it is obvious that structural changes may be employed, all without departing from the spirit of the invention, and I therefore do not desire to be limited to those precise forms as may be imposed by the following claims.

I claim:

1. A toy comprising a pair of members interconnected by a pin in spaced apart relation to form a spool-like body; each of said members being provided with a pair of longitudinal passageways therethrough, the passageways of one member being longitudinally aligned with those of the other member; and a string having one end secured to said body and carried from said securement slidingly through said passageways to form a loop portion exposed on the outer face of each of said members between the respective passageways thereof, and thence from the inner end of one of said passageways outwardly between said members by a free length, whereby said free length may be retracted by pulling said loop portions outwardly from said members.

2. A toy comprising a pair of members interconnected by a pin in spaced apart relation to form a spool-like body; each of said members being provided with a pair of longitudinal passageways therethrough, the passageways of one member being longitudinally aligned with those of the other member; and a string having one end secured to said body and carried from said securement slidingly through said passageways to form a loop portion exposed on the outer face of each of said members between the respective passageways thereof, and thence from the inner end of one of said passageways outwardly between said members by a free length, whereby said free length may be retracted by pulling said loop portions outwardly from said members; the securing of said string end being by engagement about said pin, from which engagement the threading of the string comprises carrying the string outwardly through a passageway of one member, across outside of the member and back through its other passageway to continue on through the aligned passageway of the other member, thence across the outside of the said other member and back through its other passageway.

3. A toy comprising a pair of members inter-

connected by a pin in spaced apart relation to form a spool-like body; each of said members being provided with a pair of longitudinal passageways therethrough, the passageways of one member being longitudinally aligned with those of the other member; and a string having one end secured to said body and carried from said securement slidingly through said passageways to form a loop portion exposed on the outer face of each of said members between the respective passageways thereof, and thence from the inner end of one of said passageways outwardly between said members by a free length, whereby said free length may be retracted by pulling said loop portions outwardly from said members; the securing of said string end being by engagement about said pin, from which engagement the threading of the string comprises carrying the string outwardly through a passageway of one member, across outside of the member and back through its other passageway to continue on through the aligned passageway of the other member, thence across the outside of the said other member and back through its other passageway; and a button carried by the free end of said string and of sufficient dimensions to prevent its being entered in said space.

4. A toy comprising a pair of members interconnected by a pin in spaced apart relation to form a spool-like body; each of said members being provided with a pair of longitudinal passageways therethrough, the passageways of one member being longitudinally aligned with those of the other member; and a string having one end secured to said body and carried from said securement slidingly through said passageways to form a loop portion exposed on the outer face of each of said members between the respective passageways thereof, and thence from the inner end of one of said passageways outwardly between said members by a free length, whereby said free length may be retracted by pulling said loop portions outwardly from said members; said string end securement being by a knot thereon on the outer side of one of said members; and the threading of the string consisting of having the string extend from said knot through a passageway of said one member, across said space and through the aligned passageway of the other of said members; across the outside of the said other member and back through its other passageway across said space out through the aligned passageway of said one member; across the outside of that one member and thence back through the other of its passageways into space.

CHARLES H. KUHN.
